UNITED STATES PATENT OFFICE.

JACOB DIEHL, OF CLEVELAND, OHIO, ASSIGNOR TO THE STANDARD SEWING MACHINE COMPANY, OF CLEVELAND, OHIO, A CORPORATION OF OHIO.

ROTARY TAKE-UP FOR SEWING-MACHINES.

No. 856,572.

Specification of Letters Patent.

Patented June 11, 1907.

Application filed June 16, 1903. Serial No. 161,667.

To all whom it may concern:

Be it known that I, JACOB DIEHL, a citizen of the United States, and a resident of Cleveland, in the county of Cuyahoga and State of Ohio, have invented certain new and useful Improvements in Rotary Take-Ups for Sewing-Machines, of which the following is a specification.

This invention relates to improvements in rotary take-ups for sewing machines and more particularly to rotary take-ups of the character disclosed in Letters Patent No. 669,638, dated March 12, 1901, in which the take-up makes two continuous revolutions to each reciprocation of the needle-bar and performs but one take-up or stitch-tightening operation during such time, the take-up operating to seize or pick up the thread at each alternate rotation and entirely cast off said thread during the intermediate rotations. Coöoperating with the take-up for the purpose of enabling it to thus alternately seize and cast off the thread are certain thread controlling or positioning devices, one of which is reciprocatory and attached to the needle-bar of the machine and the others stationary and attached to the face-plate of the machine. These devices, in the operation of the machine, act during one revolution of the take-up to hold the thread in a position across the path of its beak whereby the thread will be engaged and acted upon thereby, and during the second revolution of the take-up act to hold the thread away from the path of its beak so as to prevent the thread being seized thereby and permit of its being entirely cast from the take-up during such second revolution.

The thread is cast off by the take-up when the latter has performed about three fourths of its second revolution and at a time when the looper or shuttle is expanding the needle-thread loop and carrying it around to the loop discharging or cast-off side of the same. As it is necessary that the slack thread should be controlled during such time and until the thread loop is cast off by the looper, a so-called auxiliary take-up spring of usual construction is provided for controlling the slack at such time. The use of springs or spring-actuated parts, however, as well understood, are undesirable for operation at very high rates of speed, and it has therefore been one of the objects of my present invention to

avoid the necessity of the use of an auxiliary spring take-up in connection with the main rotary take-up, as disclosed in the said prior patent. This object I secure by locating a fixed or stationary device in such position relative to the take-up as to receive the thread when it is cast therefrom and properly control the slack therein in the manner as accomplished by the said auxiliary spring take-up of the patent.

Another feature of my present invention is the use of the said stationary slack-thread controlling device as a guide or controller for coöperation with the reciprocatory controller carried by the needle-bar in locating the thread in a position to be seized by the beak of the rotary take-up at each alternate rotation of the same, the position of this stationary controller device relative to the take-up and to the said reciprocatory controller being such as to enable it to perform both of the functions referred to, *i. e.* controlling the slack in the thread and positioning the same for engagement by the take-up, in the best and most desirable manner.

A further feature of my present invention is the provision of a device for preventing the thread, in the event of its accidental breakage, from being wound or otherwise entangled in the take-up, the device for performing such function in my preferred form of construction consisting of a part or extension of the said stationary thread-controller which extends into the space between the two disks or wheels of the take-up and around the end of which the broken end of the thread leading from the spool will be thrown.

Referring now to the accompanying drawings forming a part of this specification, Figure 1 is a front end view of the arm of a sewing machine with my invention applied thereto, showing the position occupied by the parts at the beginning of the take-up operation. Figs. 2, 3, 4 and 5 are similar views with my improved controller device removed, showing the position occupied by the parts at different times during the take-up operation. Fig. 6 is also a similar view, but with my improved controller device in position and its supporting plate broken away, showing the position of the parts as the thread is received by the controller just subsequent to its cast off by the take-up. Fig. 7 is a sectional view through the front end of

the sewing machine arm and supported parts taken on line 7—7 of Fig. 6. Fig. 8 is a side elevation of the machine with the casting partly broken away and showing the connections between the take-up shaft and the lower driving shaft.

In said drawings,—the head of the machine, comprising the arm A and supporting bed-plate A', the rotary shuttle or looper B, the vertically reciprocating needle-bar C, and the tension device E, are all as found in the well known "Standard" sewing machine.

The rotary take-up supported at the front end of the arm A is of substantially the same construction as that disclosed in the said prior patent before referred to, the same consisting of two skeleton disks or wheels d^2 and d^3 having a thread-passage therebetween and being connected together by pins or studs d^4 , d^5 , d^{15} , d^{16} , and d^{17} , which serve as take-up and thread-controlling crank-pins. The inner wheel or disk d^2 is attached to the forward end of the rotary take-up shaft d' by a set-screw d^6 and a clamping-washer d^7 . The outer wheel or disk d^3 is provided with a thread seizing beak or hook d^8 and forward of said beak or hook with an inclined thread guide and guard d^9 , the forward end d^{10} of which extends inwardly into engagement with the inner wheel d^2 of the take-up. Between the inclined thread guide and guard d^9 and the portion d^{12} of the outer wheel of the take-up is a gate or thread passage d^{13} leading from the space d^{14} , in which latter a bight of the needle-thread is carried during the main part of the second revolution of the take-up, as will hereinafter be more fully described.

The rotary take-up shaft d^1 , in the present instance, is journaled in the arm A and extends from the front to the rear end thereof, this shaft adjacent to its rear end being provided with a small sprocket-wheel D secured thereon which is engaged by a driving-belt b^1 running from a larger sprocket-wheel d' carried by the lower driving-shaft e^1 through the medium of a crank connection e^2 , the relative size of the said sprocket-wheels being such as to insure the take-up shaft performing two revolutions to each revolution of the driving-shaft or to each reciprocation of the needle-bar driven from said shaft, in the same manner as described in the patent hereinbefore referred to.

The devices for coöperating with the take-up in controlling the thread comprise a reciprocatory controller c in the form of an eyelet carried by the needle-bar, a stationary guide a^4 attached to the face-plate adjacent to the lower edge of the take-up and having its thread engaging edge inclined outwardly to a point in front or forward of the outer face of the take-up, and the stationary controller F of my present invention which, as

herein shown, is in the form of a thread-engaging arm carried by a supporting-plate F' in a position opposite the take-up and within the peripheral line of the same. The end of this controller arm F, as most clearly shown in Fig. 7, projects into the space between the take-up disks through an opening in the center of the outer disk, and the supporting-plate F' which carries the controller is preferably made so as to cover the major portion of the face of the take-up and serve as a guard therefor.

The operation of the invention is as follows: After a loop of needle-thread has been carried around the shuttle or looper B and is about to be cast off thereby, at which time the needle has risen to the top of its stroke, the needle-thread, which at this time extends between the stationary controller F and the reciprocatory controller c, is held by such controllers or guides in a position across the path of movement of the beak or hook of the take-up so as to be seized thereby, as shown in Fig. 1. As the take-up now continues its movement from the position shown in Fig. 1 to that shown in Fig. 2, which is about a third of a revolution or somewhat less, it operates to draw up and complete the stitch. During this take-up operation one limb of the thread-loop is in front of the outer take-up disk or wheel d^3 , while the other limb thereof is in the thread-passage between the disks or wheels d^2 and d^3 of the take-up. As the take-up continues its rotation from the position shown in Fig. 2 to that shown in Fig. 3, during which time the needle is descending, the thread is engaged by the pins d^5 and d^{15} and so controlled thereby that there will be no objectionable slack thread to get in the way of the needle, one of the said pins, indicated at d^5 , being radially adjustable within a slot d^{18} in the take-up in order to regulate its control of slack thread according to the thickness of the work being operated upon. As the take-up now continues its movement from the position shown in Fig. 3 to that shown in Fig. 4, during which it has entered on its second revolution, that limb of the thread loop formerly outside or in front of the take-up has been guided over the pin d^4 into the space between the two disks or plates of the take-up, while the other limb of the thread-loop has been guided over the inclined guide d^9 into the space d^{14} in the outer disk and has also been moved outwardly from the face of the take-up by the inclined guide-plate a^4 , so as to have permitted the beak or hook of the take-up to pass the thread without seizing it. The take-up during its second revolution now carries the bight of needle-thread in the space d^{14} in the outer take-up disk or wheel, as shown in Figs. 4 and 5, until it has performed about three-quarters of its second revolution, when the inner limb of the thread-loop passes outward through the gate or

thread-passage d^{13} and the loop is cast off entirely by the take-up and received by the controller F, as shown in Fig. 6, into engagement with which the thread had been previously guided by the passage of the outer limb of the thread loop across the face of the inwardly projecting end of the controller arm. This controller F, as hereinbefore referred to, controls and prevents undue slack thread during the latter portion of the rotation of the shuttle and prior to the cast off of the lower thread loop thereby, and also cooperates with the movable controller c in subsequently holding or positioning the thread to insure its being seized by the take-up.

The end of the controller arm projecting into the space between the take-up disks through a central opening in the outer one, as before described, insures the thread being thrown around the same instead of becoming wound or entangled in the take-up in the event of accidental breakage of the thread.

Having thus set forth my invention, what I claim and desire to secure by Letters Patent, is—

1. In a sewing machine, the combination with stitch-forming devices including a needle and a looper, of a rotary take-up having means operative to cast the thread therefrom at certain predetermined times, and a thread controller independent of the take-up and being operative to engage the thread as it is cast off by the take-up and control the slack therein during the descent of the needle and thereafter release said thread, the said controller being located in front of the take-up and having a thread guiding arm extending inwardly toward the take-up to receive the thread therefrom.

2. In a sewing machine, the combination with a rotary take-up comprising two separated disks having an intermediate take-up pin, of a stationary slack-thread controller supported in a position adjacent to said take-up and having a thread-guiding arm extending into the space between the disks of the take-up, for the purpose set forth.

3. In a sewing machine, the combination with a rotary take-up device comprising two separated disks having an intermediate take-up pin, of a stationary slack thread

controller supported in a position adjacent to said take-up and having a thread-guiding arm extending into the space between the disks of the take-up and at an angle with respect to the axis of the latter, for the purpose set forth.

4. In a sewing machine, the combination with a rotary take-up comprising two separated disks or wheels having an intermediate take-up pin, of a stationary guard-plate supported in a position in front of the said take-up and provided with an arm extending into the space between the disks or wheels of the take-up, for the purpose set forth.

5. In a sewing machine, the combination with the stitch-forming devices, of a rotary take-up comprising two separated disks having an intermediate take-up pin, means co-operative with said take-up for casting or disengaging the thread therefrom at certain predetermined times, and two thread controllers co-operative with said take-up to hold the thread in a position to be engaged thereby, one of said controllers having an arm extending across the path of movement of the take-up, for the purpose set forth.

6. In a sewing machine, the combination with stitch-forming devices, of a rotary take-up, two thread controllers co-operative with said take-up to hold the thread in a position to be engaged thereby, one of said controllers being stationary and the other being reciprocatory, and a guard supported in a position in front of the take-up and carrying the said stationary thread controller.

7. In a sewing machine, the combination with a rotary take-up comprising two separated disks having an intermediate take-up pin, of means supported in a position in front of the said take-up and provided with an arm extending into the space between the disks of the take-up, for the purpose set forth.

Signed at Cleveland, in the county of Cuyahoga and State of Ohio, this 5th day of June A. D. 1903.

JACOB DIEHL.
